UPHOLSTERY COVERING STRUCTURE

Walter I. Jones, Arlington, Mass., assignor to
United-Carr Fastener Corporation, Cambridge,
Mass., a corporation of Massachusetts

Application May 9, 1933, Serial No. 670,136

3 Claims. (Cl. 45—138)

My invention aims to provide improvements in upholstery and like covering structures and relates particularly to that portion of an upholstery installation which comprises the means for covering the frame structure.

In the drawing which illustrates preferred embodiments of my invention:—

Figure 1 is a plan of the inside of a portion of an upholstery covering structure showing a cardboard strip for holding the fastener members and showing a fastener member in the act of being turned into position;

Fig. 2 is a view similar to that shown in Figure 1, but showing the stud completely assembled with the covering structure;

Fig. 3 is a section taken on the line 3—3 of Fig. 2;

Fig. 4 is a view similar to that shown in Fig. 2, but showing a metallic fastener-holding member instead of a cardboard strip; and

Fig. 5 is a section taken on the line 5—5 of Fig. 4.

Referring to the embodiment of my invention illustrated by Figs. 1, 2 and 3 of the annexed drawing, I have shown an improved upholstery covering structure, particularly, though not exclusively, useful in connection with upholstering the interior of a motor vehicle.

The particular structure selected for illustration includes a backing 1 of cardboard or like relatively stiff material, a fastener-holding means in the form of a narrow strip 2 of cardboard and like material, a snap fastener stud member and a flexible cover 3 overlying that face of the backing 1 at that side opposite the side where the fastener-holding strip 2 is located. The flexible cover 3 is preferably wrapped over the edge of the backing 1, as illustrated in Figs. 1 and 2. The fastener-holding strip 2 may be provided in any suitable manner and I have illustrated it as being a separate narrow strip secured in position by spaced apart staples or metal stitches 4, as clearly illustrated by the drawing. Any number of snap fastener members may be used, as will be understood by those skilled in the art. However, I have shown a single fastener because the others are merely duplicates of the same structure.

Since it is preferable to manufacture the upholstery covering structure as a complete unit prior to attachment of the snap fastener members, I have provided a new, useful and very simple structure whereby the fastener member may be attached and detached by a simple rotary operation. In the structure illustrated in Figs.

1 through 3 there is shown an elongated, rectangular aperture 5 extending through the fastener-holding strip 2. The snap fastener member is in the form of a stud of well known construction and has a base 6 which is flat and relatively thin. The base 6 is of larger area than the aperture 5 so that when it is located between the cardboard backing 1 and the strip 2 (Fig. 3) it cannot become accidentally displaced from the covering structure. The stud member also includes a yieldable shank provided by a pair of relatively thin projections 7 (Fig. 1) extending from the base through the aperture 5 for engagement with the frame structure in the usual manner. The projections 7 are relatively thin but overlap each other for a scissors-like relative movement. The base 6 has a notch 8 extending inwardly from the periphery toward the yieldable shank of the stud.

In order to attach or detach the stud when the upholstery structure is complete, it is merely necessary to enter one of the ends 9—9 at opposite sides of the notch 8 through the aperture 5 (Figure 1) and then rotate the stud member. This action causes the base to turn into position between the cardboard backing 1 and the fastener-holding strip 2, as illustrated in Figs. 2 and 3. When the fastener is in position it is held against axial movement by the imperforate backing and those portions of the strip 2 adjacent to the aperture 5. The stud is freely shiftable laterally in all directions so that the yieldable shank may be aligned with an aperture provided by a frame structure not shown.

The structure illustrated in Figs. 4 and 5 is the same as that described in connection with Figs. 1 through 3 with the exception of the form of the fastener-holding member. Therefore, numerals for similar parts will be used in connection with Figs. 4 and 5.

Instead of using a cardboard strip as a fastener-holding means, I have shown an individual metallic plate 10 which is attached directly to the backing 1 by prongs 11 extending into hook-shaped embedded relation with the backing, as best illustrated in Fig. 5. The plate 10 is preferably provided with an offset portion 12 so as to space the front face thereof away from the cardboard backing, thereby providing a space for the base 6 of the stud member. The aperture 13 formed in the plate 10 is of fixed dimensions, elongated and is surrounded by a continuous peripheral wall 14, as best illustrated in Fig. 4.

Attachment and removal of the stud from the

installation shown in Figs. 4 and 5 is substantially identical with the manner in which the stud member is attached and detached from the installation shown in Figs. 1 through 3 and, 5 therefore, needs no further description.

My invention, as illustrated and described, is particularly useful, since the number of parts for the installation has been reduced to a minimum without sacrificing any advantages which 10 more complicated structures may have. Furthermore, my invention presents certain new and useful improvements, since the fastener members are easy to attach and when once attached cannot be removed except when it is desirable 15 to do so.

While I have illustrated and described preferred embodiments of my invention, I do not wish to be limited thereby, because the scope of my invention is best defined by the following claims.

20 I claim:

1. An upholstery and like covering structure including a cardboard and like backing, a relatively rigid fastener-holding means presented at one face of the backing and having a portion 25 with a hole therethrough spaced from said backing, said backing being imperforate beneath the hole through the fastener-holding means, a snap fastener member having a base of larger area than the aperture in said fastener-holding means 30 and bearing at one side against the backing and at the other side against the apertured portion of the fastener-holding means and said base

having means constructed and arranged to permit passage of said base through said aperture only by rotary movement of said fastener.

2. An upholstery and like covering structure including a cardboard and like backing, a fastener-holding metallic plate secured against one face of the backing and having a hole therethrough surrounded by a continuous wall, a snap fastener member having a base longer in one direction than the longest dimension of the aperture in said plate and being located beneath said plate, and said base having a notch constructed and arranged to permit passage of the base through the hole in the metallic plate by rotary movement of said fastener. 15

3. An upholstery and like covering structure including a cardboard and like backing, a fastener-holding piece formed of cardboard and located at one face of the backing, said cardboard piece having an aperture therethrough of fixed 20 dimensions surrounded by a continuous wall, the backing being imperforate beneath the fastener-holding means, a snap fastener member having a base of larger area than the aperture in said plate and being located between the backing and 25 the cardboard piece, and said base having a notch extending inwardly from one edge thereof to permit passage of the base through the aperture in the cardboard piece by rotary movement of said fastener. 30
